(57) **CLAIM**

The ornamental design for a merchandise display fixture, as
shown and described.

DESCRIPTION

FIG. 1 is a front, perspective view of a merchandise display
fixture showing our new design;

FIG. 2 is a rear, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a front, perspective view of the merchandise display
fixture of FIG. 1 showing our new design with additional
unclaimed environmental subject matter;

FIG. 10 is a rear, perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The features shown in broken lines are portions of the mer-
chandise display fixture or environmental subject matter to
the merchandise display fixture forming no part of the
claimed design.
